FIG. 2.

UNITED STATES PATENT OFFICE

WLADYSLAW PIJAKOWSKI, OF CHICAGO, ILLINOIS

SWIMMING DEVICE

Application filed June 8, 1931. Serial No. 542,901.

The present invention relates to swimming devices and has for its main object the provision of a device which would facilitate swimming.

5 A further object of the present invention is the provision of a swimming device consisting of a paddle fastened to the body of the swimmer and which may be angularly shifted on backward stroke of the swimmer's leg for propelling the swimmer in the water.

With the above general objects in view and others that will appear as the nature of the invention is better understood the same consists in the novel construction, combination and arrangement of parts hereinafter more fully described and illustrated in the accompanying drawings and pointed out in the appended claims.

In the drawings forming a part of this application and in which like designating characters refer to corresponding parts throughout the several views,

Fig. 1 shows a person in the act of swimming in the water illustrating the manner of attaching the device to the swimmer's body and further illustrating the manner of operating the device;

Fig. 2 is a front elevational view of the present device;

Fig. 3 is a cross-sectional view on line 3—3 of Fig. 2;

Fig. 4 is a side view of means for anchoring the device to its base;

Fig. 5 is a modified form of tensioning and anchoring means of the device to its base;

Fig. 6 is a cross-sectional view on line 6—6 of Fig. 5;

Fig. 7 is a side elevational view of two portions of telescopically extensible rod with locking means therebetween;

Fig. 8 is a similar side elevational view showing a modified form of locking means;

Fig. 9 is a similar view showing another form of locking means;

Fig. 10 is a similar view with still another form of locking means;

Fig. 11 is an edge or front view of still another modification of locking means;

50 Fig. 12 is an elevational view of a modi-

fied form of the propelling plate or paddle;

Fig. 13 is a fractional view of the paddle and the rod to which the same connects, showing the hinge connection therebetween;

Fig. 14 is a similar view illustrating another hinge connection between the paddle and the rod, said connection being of the same type as that shown on Fig. 12; and

Fig. 15 is a cross-sectional view through a pulley attachable to the swimmer's leg adapting the device to be operable by the swimmer's arm instead of a leg.

Referring in detail to the present drawings, there is shown therein base 16 attached to belt 17 which is adapted to encircle swimmer's waist as seen on Fig. 1.

Mounted upon base 16 by means of nails, rivets or the like, 18, is a U-shaped plate 19. Pivoted to each of the two free ends of said U-shaped plate 19 upon rivet 20 is arm 21, each of said arms 21 adjacent one of its ends is horizontally bent as at 22 in the direction towards each other and thereupon the ends of each of said arms 21 meet to form extension 23 for receiving thereupon tubular member 24. The lower free ends of each of said arms 21 and adjacent their edges nearest to base 16 is provided with notch 25 affecting a hook 26 in each of said ends for attaching therewithin loop 27 of spring member 28. A similar spring member by its loop 29 is anchored at base 16 by means of nails 30 or other similar means. Both of said spring members in each of spring devices cooperating with each of said arms 21, are adapted to receive coil spring 31, the ends of each of said spring members being bent as at 32, for the purpose of maintaining coil spring 31 in position within each of said spring devices. Said coil spring 31 is contracted for the purpose of normally exerting tension upon the bent ends 31 of each of said spring members 28 in each of the spring devices so that each of said spring devices may exert a pulling pressure upon each of the lower ends of said arms 21.

Thus, the action of said spring devices maintains arms 21, extension 23 and tubular member 24 in substantially parallel relation with pipe 16.

The modified form of the spring device for the same object is illustrated on Figs. 5 and 6 and includes plate 33 attached to base 16 by means of screws 34. Adjacent the opposite edges said plate 33 has wings 35 made from the body of the plate 33, which wings are formed by making incisions within the body of plate 33, along lines 36. Said wings are thereupon bent to assume angular position with respect to plate 33. Positioned within said wings 35 is bolt 37 with its head 38 contacting with one face of one of said wings 35. The other end of bolt 37 is threaded to receive nut 39. Positioned upon said bolt 37 is a pair of coil springs 40 and 41, each having its outer ends resting upon plate 33 as at 42. The other ends of said coil springs 40 and 41 meet substantially at the central portion of bolt 37 and the inner ends of said springs meet there and affect extensions 43 to receive thereupon tubular member 24. It is observed that spiral of springs 40 and 41 wind in opposite directions, by virtue whereof both of said springs act uniformly and in unison. Said springs are further so arranged that said extension 43 made of two inner meeting ends of springs 40 and 41 remains normally in parallel relation with plate 33 and base 16. When the tubular extension 24 is angularly shifted with respect to base 16, which action will be hereinafter described, this shifting movement is accomplished against the tension of springs 40 and 41, and conversely, when the pressure at tubular member 24 is eliminated, which action of springs 40 and 41 automatically brings said tubular member 24 to its normal original position.

Frictionally receivable at the other end of tubular member 24 and telescopically extensible therewithin is rod 44, which has substantially rectangular formation on cross-section. Said rod 44 at one of its edges is provided with a plurality of spaced notches 45 made transversely of rod 44 for the purpose which will be hereinafter described.

Adjacent the end within which said tubular member 24 receives rod 44 said tubular member is provided with a U-shaped clamp 46, tightened by means of rivet or screw 47. Mounted upon said screw 47 is locking device formed out of a single wire which includes coils 48. One of said ends of the locking device is adapted to rest upon one edge of tubular member 24 as at 49. The opposite end extends beyond the adjacent end of tubular member 24 and is transversely bent to affect arm 50. Said coils 48 are so formed as to exert tension upon end 49 to hold the same in close contact with the adjacent edge of tubular member 24 as well as to drive arm 50 towards the adjacent edge of rod 44. Said arm 50 is adapted to spring within anyone of notches 45 made in rod 44. In order to withdraw arm 50 from with-

in notch 45 the free end of said arm 50 is provided with loop 51 whereby the same may be manually grasped in order to withdraw arm 50 from within notch 45 when it becomes necessary or desirable either to extend rod 44 from within tubular member 24 or to further drive the same within said tubular member 24.

The modified form of the locking device for tubular member 24 and rod 44 as shown on Fig. 8 includes similar clamp 46 and screw 47. There, however, wire member 52 is pivotally positioned upon screw 47 by being provided with a suitable loop encircling said screw 47. Coil spring by one of its ends is adapted to contact with the adjacent edge of tubular member 24 as at 53, while the other end of coil spring is transversely bent affecting transverse arm 54 resting upon the other end of wire member 52. Said end of wire member 52 is likewise transversely bent to affect transverse arm 55 which is adapted to spring into one of notches 45. On manually exerting pressure at loop 56 of wire member 52 the other end of said wire member 52 with its arm 55 may be angularly shifted against the tension of spring arm 54, and away from the contacting edge of rod 44.

The locking device shown on Fig. 9 contemplates making wings 57 which are cut out from the narrower edges of tubular member 24. These wings 57 are bent to assume parallel relation and to remain on the same plane with the plane of said narrower edges of tubular member 24. Rivet, bolt or screw 58 is passed through said wing 57 to receive thereupon tensioning coils 59 of wire member 60. By virtue of springy action of said tensioning coils 59 and of said wire member 60, adjacent tubular member 24 is adapted to contact with the adjacent face of said tubular member 24. A similar action is had at the opposite end of said wire member 60 for driving the same towards the adjacent face of rod 44'. Said rod 44' instead of having notches such as notches 45 in the preferred form of rod 44 is provided with a series of apertures 61 made in the body of the rod for receiving therewithin lug 62 which is mounted upon the adjacent end of wire member 60. By manually grasping at head 63 of lug 62 said lug 62 may be withdrawn from aperture 61 and against the tension of coils 59.

The locking device illustrated on Fig. 10 includes a similar clamp 46 and screw 47 by means of which the former is attached to tubular member 24. A double wire member by its coils is positioned upon screw 47, each coil remaining adjacent the inner faces of free ends of clamp 46. One end 64 of the wire member contacting with the adjacent edge of tubular member 24. The other end of said wire member being formed into a U-shaped arm 65 of which the transverse portion is adapted to enter one of notches 46 of rod 44.

By virtue of action of coils, which are of springy nature, the U-shaped arm 65 is urged towards the adjacent edge of rod 44. The locking device further includes lever arm 66 pivoted upon screw 47 and between the coils of the wire member. One end of said lever arm 66 is formed into a transverse buckle 67 encompassing and engaging the sides of the U-shaped arm 65. The other end of said lever arm 66 terminates in loop 68 for facilitating manual operation thereof. On exerting manual pressure at loop 68 U-shaped arm 65 may be raised against the tension of its coils set upon screw 47 for lifting the transverse portion of said arm 65 from within notch 45.

The locking device illustrated on Fig. 11 is similar in its construction to that shown on Fig. 10, and includes clamp 46 held in position upon tubular member 24 by means of screw 47. Ends 64 of wire member rest upon the adjacent edge of tubular member 24, coils 69 thereof being set upon said screw 47, and the other end of wire member terminates in a similar U-shaped arm 65. Lever 66 is set upon screw 47 by its loop 70. In this form of the locking means the buckle 67 remains below the sides of U-shaped arm 65. On exerting pressure at the free end of lever 66 buckle 67 is adapted to raise U-shaped arm 65 from its engagement with rod 44 within notch 45.

Although I have shown several forms of locking means between tubular member 24 and rod 44, on Figs. 7 to 11, both inclusive, it is understood that various other locking devices may likewise be employed.

Referring again to Fig. 2, the outer end of rod 44 carries a paddle for propelling water and includes a pair of substantially oval shaped plates 71 which are hingedly connected upon pintle 72, which, at one of its ends is provided with head 73, and the other end thereof being screw-threaded as at 74 for receiving thereupon nut 75. Positioned upon said pintle 72 and substantially at a central portion thereof there is clamp 76, the two wing portions thereof passing through suitable slots 77 formed in the adjacent portions of plates 71. Said wing portions of clamp 76 receive therebetween rod 44 which is positioned in the rear of said plates 71. Screw 78 passing through ends of said clamp 76 and nut 79 is adapted to rigidly mount said clamp 76 upon said rod 44, whereby said plates 71 are affixed to rod 44 and act as a paddle for propelling water as will be hereinafter described.

Affixed by rivet 80 or by any other suitable means to one of plates 71, at the rear face thereof and adjacent its edge nearest to the hinge pintle 74 is one or more lugs 81, which extend in the path of movement of the other plate 71 whereby its further rearward movement may be limited.

Positioned adjacent each end of pintle 74 is coil spring 82 with its ends 83 resting and

bearings against the front faces of plates 71, for the purpose of normally maintaining said plate 71 in an open position shown on Fig. 2.

Attached to rod 44, at a point below said lower terminations of plates 71, by means of screw 84 is eye 85 to which chain 86 is fastened by one of its ends. Said chain in Fig. 1 is partially broken away in order not to obscure the view of parts of the device remaining beyond it.

The other end of chain attaches to stirrup 87 the horizontal portion whereof has set thereupon cork or any other suitable roller 88 to provide a foot rest.

Referring to the operation of the present device, on the backward stroke of the swimmer's leg rod 44 and tubular member 24 will be angularly shifted against the tension of coil springs 31 or coil springs 40 and 41, as the case may be, to assume position perpendicular to the body of the swimmer, as shown by dotted lines on Fig. 1. During angular shifting of said rod 44 and tubular member 24 plates 71 will remain open as illustrated on Fig. 2, lugs 81 prevent further opening or backward angular shifting of said plates 71. Thus, said plates 71 moving against the irre sistence of water will propel the swimmer forwardly.

On the forward stroke of the swimmer's leg tension at chain 86 will be released, in consequence whereof coil springs 31 or springs 40 and 41, as the case may be, will bring rod 44 and tubular member 24 to its inoperative position, shown by full lines on Fig. 1. During the return of plates 71 to its inoperative position, plates 71 meeting the resistance of water from the opposite side will close against the tension of ends 83 of coil springs 82.

To adapt the device for operation by swimmer's arm instead of a leg, pulley 89, best shown on Fig. 15, is provided. This pulley is mounted upon shaft 90 one end of which receives nut 91 and is countersunk within central slot 92 made in one face of said pulley 89. Said pulley 89 is adapted for free rotation upon said shaft 90. The other end of said shaft 30 is adapted to receive arm 93 which is held in position against the other face of pulley 89 by means of head 94 integrally formed with shaft 90. The other end of arm 93 has clasp 95 which is adapted to receive belt 96 attachable to swimmer's leg above the knee. Chain 86 may then be passed over said pulley 89, flanges 97 upon said pulley 89 preventing easy displacement of said chain 86. Thereupon stirrup 87 is grasped at by swimmer's hand, and on forward stroke of the arm plates 71 will make angular shifting movement rearwardly against the water for propelling the swimmer forwardly.

On rearward stroke of swimmer's arm the pressure of rod 44 and tubular member 24 by chain 86 will be released and said plate 71 will be allowed to

assume an inoperative position shown by full lines on Fig. 1.

Figs. 12 and 14 illustrate a modified form of the paddle and hinge connection thereof with rod 44. In this form the paddle comprises three plates, the outermost two being hinged to the center one by means of hinges 99. Attached to the central plate 98 are lugs 100, portions of which extend beyond the adjacent edges of said central plate 98 to remain in the path of movement of the outward plates 98, for limiting further movement of said outer plates 98 when the same are in an open position during the operative stroke of the paddle in the water. This construction of the paddle allows the folding of plates 98 one upon the other when the device is not in use. The hinge connection between the paddle and rod 44 includes a pair of wire members 101 provided with loops 102 which are arranged in parallel relation with the central plate 98. Said loops are adapted to be impinged between the heads of screws 103 and the adjacent face of central plate 98.

The other ends of wire members 101 extend beyond the adjacent edge of central plate 98 and terminate in loops 104 which are on a plane perpendicular to said central plate 98. These latter loops are freely positioned upon screw 105 which passes through rod 44 and remains in a transverse relation therewith. Head of screw 105 and nut 106 receiveable at the other end of screw 105 hold said screw in position upon rod 44 and prevent loops 41 from making any lateral movement. Thus, said wire members 101 make an efficient hinge connection which is simple in construction.

This modified form of the paddle is adapted to bodily angularly shift upon screw 105 through the medium of loops 104.

The opposite face of central plate 98 is adapted to bear against the reduced edge 107 adjacent the end of rod 44, for limiting further angular shifting movement of the paddle.

The modified form of the hinge connection between plate 98 and rod 44, illustrated on Fig. 13, includes wire members 108 positioned on the opposite faces of plate 98. Loops 109 at one end of said wire members 108 are set upon screw 110 passing through plate 98. The opposite ends of said wire members 108 pass beyond the adjacent edge of plate 98 and terminate in loops 111, which are made on a plane vertically of the plane running through loops 109. These loops 111 are positioned upon screw 112 passing through rod 44.

While there is described herein a preferred embodiment of the present invention it is nevertheless to be understood that minor changes may be made therein without departing from the spirit and scope of the invention as claimed.

What I claim as new is:

1. In a swimming device, a body encircling

belt, a substantially flat hollow member pivoted on said belt, resilient means normally maintaining said member parallel with the belt, a rod telescopically received in one end of said member, a paddle carried by one end of said rod and including swingingly mounted spring influenced sections, a clamp carried by said member adjacent one end thereof, a locking element yieldably pivoted on said clamp and including a portion to engage and hold said rod fixed relatively to said hollow member in a given position, a flexible element terminally connected with said rod, and a stirrup connected with the free end of said flexible element to move said member against the influence of said resilient means.

2. In a swimming device, a body encircling belt, a substantially flat hollow member pivoted on said belt, resilient means for normally maintaining said member parallel with said belt, a rod having a flat portion telescopically received by said member and provided with spaced notches along one edge, a paddle carried by the outer portion of said rod and including swingingly mounted spring influenced sections, a clamp carried by the hollow member adjacent the outer end thereof, a locking element formed from a single length of wire and including a spring coil supported by the clamp, and an angular extension engaging one of said notches to hold the rod fixed relatively to the member in any given position, a flexible element connected with said rod, and a stirrup carried by the free end of said element to move the member and rod as a unit against the influence of said resilient means.

In testimony whereof I have affixed my signature.
